UNITED STATES PATENT OFFICE.

EDWARD E. CLEMENT, OF WASHINGTON, DISTRICT OF COLUMBIA.

ELECTRIC SWITCH.

1,107,153.

Specification of Letters Patent. Patented Aug. 11, 1914.

Original applications filed July 15, 1907. Serial No. 383,875, and April 18, 1910, Serial No. 556,213. Divided and this application filed June 29, 1910. Serial No. 569,696.

To all whom it may concern:

Be it known that I, EDWARD E. CLEMENT, a citizen of the United States, residing at Washington city, in the District of Columbia, have invented certain new and useful Improvements in Electric Switches, of which the following is a specification, reference being had therein to the accompanying drawing.

10 My invention relates to electric switches and has for its object the production of a simplified form of a selective step by step switch having multiple arms and bank contacts arranged in the segment of the circle instead of in a complete circle; whereby the contents are made accessible and the bank is rendered open, without loss of continuity in action.

This application is a division of my prior 20 application, Serial No. 556,213, filed April 18, 1910, as to the disclosure in Figures 1 to 4 inclusive; and as to the disclosure in Fig. 5 a division of my prior application, Serial No. 383,875, filed July 15, 1907, 25 wherein is specifically disclosed a bank of contacts arranged in the arc of a circle, a spindle, and a plurality of connected wiper arms (three) mounted on said spindle and spaced apart thereon at angular distances 30 representing the same fraction of a circle (120°) as the angular length of the arc of contacts, whereby by rotating the spindle, continuous engagement may be had between the wiper arms and the bank contacts, yet 35 with only one arm engaging the contacts at a time. The specific construction of the operating means for the wiper arms is on the other hand the same as that disclosed in Figs. 1 to 4, and a division of Serial No. 40 556,213 as aforesaid.

My invention is illustrated in the accompanying drawings in which—

Fig. 1 is a plan view of the switch, Fig. 2 is a side view thereof, Fig. 3 is a face view 45 of part of a bank removed. Fig. 4 is an end view of the switch. Fig. 5 is a plan view of a modification.

Referring to the drawings, the switch is generally designated by the letter S, and comprises three essential elements, viz. (1) a bank of contacts s, (2) an electromagnet propelling unit s', and (3) wiper arms s² carried on a central spindle s³, and driven by the magnet to coöperate with the bank of contacts.

Fig. 3 shows part of a bank removed from the switch, which is accomplished by taking out the screws s⁴ which fasten the ears s⁵ to the posts s⁷ constituting extensions of the frame s⁸ upon which the magnet unit s' is 60 likewise mounted by means of screws s⁹.

The spindle s³ is rotated by means of a ratchet wheel s¹⁰ engaged by a pawl s¹¹ carried upon the end of the aluminum armature lever s¹² which is secured at the 65 other end to the iron armature s¹² of the electromagnet. The lever s¹² is formed of aluminum in a hollow shape for stiffening purposes and at the armature end is provided with a right angle extension s¹³ having lateral wings s¹⁴ overlapping the iron armature s¹² and riveted thereto. The armature is transversely scored at s¹⁵ to receive 70 a knife edge s¹⁶ which is given a sliding adjustment by providing it with slots working 75 in the set screws s¹⁷. Outside of the knife edge a pair of coiled springs s¹⁸ is provided, each secured at one end to an ear s¹⁹ formed on the frame, and the other end passing over the shank of a screw s²⁰ whose head is held 80 by an ear s²¹ forming an extension of one of the wings s¹⁴. By turning the screws s²⁰, the tension of the springs may be adjusted.

It should be understood that the magnet s' comprises a pair of cores s²² arranged side 85 by side and parallel to each other. These cores are united at their rear ends by an iron yoke s²³ and when energized act jointly upon the iron armature s¹². When current flows through the windings and the armature is attracted the lever arm s¹² is thrown to the left in Fig. 1, forces the pawl s¹¹ into one of the teeth of the ratchet wheel s¹⁰, rotating the wiper s² in the direction of the arrow. At the end of one step a positive 90 stop is furnished by a heel piece s¹¹¹ on the pawl coming in contact with the frame. The toe of the pawl is kept pressed into engagement with the ratchet by means of a short 95 spring s¹²⁰.

It will be observed that the wiper arm is double, and upon close examination of Fig. 1 it will be found that one arm s² comes upon the first contact just as the other arm s²⁰⁰ is leaving the last contact. This arrangement 105 permits the contact bank to be made open or in the arc of a circle instead of a complete circle, which latter would have to be employed if only a single wiper arm were 110 available. Such a multiple wiper to permit

the use of an open contact bank is new and original with me and I shall therefore claim the same as a part of my invention, together with sundry details of the switch shown in 5 Figs. 1 to 3.

In Fig. 5 I have shown a modification in which there are three pairs of wiper arms set 120° apart. The contact bank in this case extends through a little less than 120° , 10 or one-third of a circle. The effect is the same as above described, that is to say each wiper arm will leave the last contact in the bank just as its successor comes on the first contact, thereby giving a continuous test with 15 an open bank.

Having thus described my invention what I claim and desire to secure by Letters Patent is—

1. An electric switch comprising a frame, 20 a bank of contacts in the arc of a circle with interposed insulation mounted in said frame, wipers pivoted on the frame so as to sweep over the contacts, a ratchet wheel connected with the wipers, and an electromagnetic unit 25 for driving the ratchet comprising an iron core end-supported on the frame with its axis extending toward the axis of the wipers, a winding on the core, a fixed bearing near the free end of the core, an iron armature adapted 30 to rock on said bearing and extending into proximity to said free end of the core as a pole piece, a relatively light lever struck from sheet material connected at one end to said armature and extending along the magnet 35 substantially parallel to the core into proximity to the wiper ratchet, and a pawl pivoted in the end of the lever and engaging the ratchet, said lever and armature together constituting a bell crank and the lever being 40 formed up with a hollow rib in its body extending beyond and around its junction with the armature so as to stiffen the structure and prevent springing or flexing in the plane of its motion.
2. An electric switch comprising a frame, 45 a bank of contacts in the arc of a circle with interposed insulation mounted in said frame, wipers pivoted on the frame so as to sweep over the contacts, a ratchet wheel connected 50 with the wipers, and an electromagnetic unit for driving the ratchet comprising an iron core supported on the frame from one end and having its other end projecting laterally therefrom, a winding on the core, a fixed 55 bearing near the free end of the core, an iron armature adapted to rock on said bearing and extending into proximity to said free end of the core as a pole piece, a lever formed of light non-magnetic material connected 60 at one end to said armature and extending along the magnet substantially par-

allel to the core into proximity to the wiper ratchet, and a pawl pivoted in the end of the lever and engaging said ratchet, said lever and armature together constituting a bell 65 crank, and the lever being provided with stiffening means at its juncture with the armature to prevent springing or flexing in the plane of its motion.

3. An electric switch comprising bank contacts, a co-operating wiper and means for driving the same, together with a control magnet unit therefor composed of the following instrumentalities: a pair of parallel cores s^{22} carrying windings s' and united by 70 a yoke s^{23} , a frame or return bar extending parallel to the magnet cores and carrying a knife edge extending transversely to and overlying the free ends of the cores, an iron armature engaging said knife edge and extending across the core-ends, a lever of light non-magnetic material formed in bell crank shape with a stiffening rib around its angle, its short member being secured to the iron armature and its long member extending 75 parallel to the cores into operative proximity to the wiper actuating means, and a pair of symmetrically disposed coiled springs each secured at one end to the yoke end of the magnet structure and at the other end to 80 a projection on the armature outside of the point of attachment of the lever, both of said springs being normally under tension and acting to withdraw the armature from the pole pieces and to maintain said armature 85 in constant engagement with the knife edge.

4. An electric switch comprising an open bank of contacts formed in the arc of a circle, and a double wiper arm having contacts at both ends adapted to be rotated in continuous engagement with said bank contacts, but with only one end engaging at the same time.

5. An electric switch comprising a bank 90 of contacts arranged in the arc of a circle, a spindle, and a plurality of connected wiper arms mounted on said spindle and spaced apart thereon at angular distances representing the same fraction of a circle as the angular length of the arc of contacts, whereby 95 in rotating the spindle, continuous engagement may be maintained between the wiper arms and the bank contacts, only one arm engaging the contacts at the same time however.

In testimony whereof I affix my signature in presence of two witnesses.

EDWARD E. CLEMENT.
